DISPLAY CABINET

Clare Kafer, Palmyra, Mich., assignor to Reveo, Inc., Deerfield, Mich.

Application May 4, 1950, Serial No. 9,700

Term of patent 7 years

(Cl. D80—11)

To all whom it may concern:

Be it known that I, Clare Kafer, a citizen of the United States residing at Palmyra in the county of Lenawee and State of Michigan, have invented a new, original, and ornamental Design for a Display Cabinet, of which the following is a specification, reference being made to the accompanying drawing, forming a part thereof.

In the drawing, Fig. 1 is a top plan of a display cabinet showing my new design;

Fig. 2 is a front elevational view;

Fig. 3 is an end elevational view;

Fig. 4 is a rear elevational view with the doors in an open position; and

Fig. 5 is a rear elevational view with the doors in a closed position.

I claim:

The ornamental design for a display cabinet, as shown.

CLARE KAFER.
